CLAIM

The ornamental design for a vehicle wheel, as shown and described.

DESCRIPTION

FIG. 1 is a front view of a vehicle wheel showing the new design;

FIG. 2 is a left front perspective view thereof;

FIG. 3 is a left rear perspective view thereof;

FIG. 4 is a rear-side perspective view thereof; and,

FIG. 5 is a rear view thereof.

In the drawings, the elements shown in broken lines are for illustrative purposes only and form no part of the claimed design.
